INVENTOR.
Nathan Warshaw
BY
M. J. Riswell, ATTORNEY

UNITED STATES PATENT OFFICE.

NATHAN WARSHAW, OF NEW YORK, N. Y.

FAN.

1,424,864.

Specification of Letters Patent. Patented Aug. 8, 1922.

Application filed June 15, 1921. Serial No. 477,694.

To all whom it may concern:

Be it known that I, NATHAN WARSHAW, a citizen of Russia, and a resident of New York, in the county of New York and State 5 of New York, have invented certain new and useful Improvements in a Fan, of which the following is a full, clear, and exact specification.

This invention relates more particularly 10 to a class of air circulating devices.

My invention has for its object primarily to provide a fan designed to be employed by persons for fanning purposes, and which is of a form whereby the device may be made 15 of inexpensive material, such as cardboard and the like, so that if desired it may be given away or sold at an unusually moderate price, it being contemplated to use the fan especially for displaying attractive advertising matter. The invention resides 20 mainly in the provision of a stiffener or rigid metallic tubular handle element having an approximately U-shaped part with the end portions of its legs being flared in outwardly 25 diverging directions, and in the entire inner edge of the handle element is a continuous slot. This element is applied to a fan having a body section with a protruding portion, both made of flexible material, by 30 the marginal edge of the protruding portion and the adjacent marginal edge parts of the body section being securely arranged in the slot of the element so that the fan will be sufficiently stiffened to allow of being 35 employed by a person in the manner common to the use of ordinary fans.

A further object of the invention is to provide a fan of a simple and efficient construction which may be made in any suitable 40 size.

With these and other objects in view, the invention will be hereinafter more fully described with reference to the accompanying drawing forming a part of this specification 45 in which similar characters of reference indicate corresponding parts in all the views and will then be pointed out in the claims at the end of the description.

In the drawing, Figure 1 is an elevation 50 of one form of fan embodying my invention.

Fig. 2 is an elevation of the handle element used on the fan, and

Fig. 3 is a section taken on the line 2—2 55 of Fig. 1.

The fan has a body section 10 which may be oval, circular or other shape of an appropriate size, and integral with part of the edge of the body section 10 is a protruding portion 11 which may be substantially lobular or U-shaped for serving as a handle to permit a person to manipulate the device in a fashion similar to using fans of ordinary types. The body section 10 and the protruding or handle portion 11 may be made 60 of any suitable flexible material, such as cardboard, so that the fan may be used for various advertising purposes if desired by printing or embossing or otherwise providing thereupon attractive subject matter. 65 When made of cardboard the flexibility of the handle portion 11 will tend to prevent the fan from being practical for general use, and to overcome this objection the handle or protruding portion 11 as well as the adjacent part of the body section 10 are reinforced or stiffened by a handle element, 70 as 12.

This handle element has a substantially U-shaped or lobular part 13 to provide 75 spaced legs 14 and 15 and a spanning member 16. The end parts of the legs 14 and 15 are flared in outwardly diverging directions, as at 17 and 18. These parts of the handle element are preferably made of circular tubular metal, and the parts are of proportions and of formations conforming to the shapes and sizes of the handle portion 11 and contiguous parts of the edge of the body section 10 of the fan. In the inner 80 curvature or edge of the tubular handle element 12 is a continuous slot, as 19, and in this slot is disposed the marginal edge parts of the handle portion 11 and the adjacent marginal edge parts of the body section 10 85 of the fan. The edges of the slot 19 are forced toward each other into tight engagement with the handle portion 11 and body section 10 of the fan for securing this element to the body section and to the handle 90 portion so that the fan may be advantageously used in the usual manner by a person. 95

In the foregoing description, I have embodied the preferred form of my invention, 100 but I do not wish to be understood as limiting myself thereto, as I am aware that modifications may be made therein without departing from the principle or sacrificing 105 any of the advantages of this invention, 110

therefore I reserve to myself the right to make such changes as fairly fall within the scope thereof.

Having thus described my invention, I claim as new and desire to secure by Letters Patent:—

A fan, comprising a flexible body section with a flexible substantially U-shaped protruding portion, and a metallic tubular handle element also having an approximately U-shaped part with the end portions of its legs being flared in outwardly diverg-

ing directions and the entire inner edge of the handle element having a continuous slot in which the marginal edge of the protruding portion and the adjacent marginal edge parts of the body section are fixedly disposed. 15

This specification signed and witnessed this 14th day of June A. D. 1921.

NATHAN WARSHAW.
